US00D856757S

(12) **United States Design Patent** (10) **Patent No.:** **US D856,757 S**
Seiders et al. (45) **Date of Patent:** ** *Aug. 20, 2019

(54) **BOTTLE**(71) Applicant: **YETI Coolers, LLC**, Austin, TX (US)(72) Inventors: **Roy Joseph Seiders**, Austin, TX (US);
Matthew Joseph Petrillo, Austin, TX (US);
Steve Charles Nichols, Austin, TX (US)(73) Assignee: **YETI Coolers, LLC**, Austin, TX (US)

(*) Notice: This patent is subject to a terminal disclaimer.

(**) Term: **15 Years**(21) Appl. No.: **29/604,120**(22) Filed: **May 15, 2017**(51) LOC (12) Cl. **07-01**

Primary Examiner — Terry A Wallace(74) *Attorney, Agent, or Firm* — Banner & Witcoff, Ltd.(57) **CLAIM**

The ornamental design for a bottle, as shown and described.

DESCRIPTION

FIG. 1 is a top, front, right perspective view of a bottle showing our new design;

FIG. 2 is a bottom, front, right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom thereof.
